UNITED STATES PATENT OFFICE.

WILFRED E. BOUGHTON, OF PHILADELPHIA, PENNSYLVANIA, ASSIGNOR, BY
MESNE ASSIGNMENTS, TO THE LORAIN STEEL COMPANY, OF OHIO.

ELECTRIC-MOTOR TRUCK.

SPECIFICATION forming part of Letters Patent No. 633,713, dated September 26, 1899.

Application filed September 12, 1898. Serial No. 690,747. (No model.)

To all whom it may concern:

Be it known that I, WILFRED E. BOUGHTON, of Philadelphia, in the county of Philadelphia and State of Pennsylvania, have invented a new and useful Improvement in Electric-Motor Trucks, of which the following is a full, clear, and exact description, reference being had to the accompanying drawing, which forms a part of this specification.

My invention relates to that class of trucks for electric-railway vehicles which are adapted to carry electric motors for propelling the vehicle; and it consists of a certain improved construction, which, with the purposes to be gained thereby, will be hereinafter duly set forth. In trucks of this character it is necessary to frequently examine and often to remove the electric motors for the purpose of repairs. It is also necessary to remove one or more of the wheels from time to time as they flatten or wear out and replace the same with others which are in good condition.

It is one object of my invention to provide a truck in which the construction is such that the motors can be very readily inspected, handled, or removed and the wheels be quickly removed when necessary. Ordinarily in repairing electric motors it is customary to run the vehicle over a pit, so that the workman may reach the motor from below and make whatever repairs or tests are necessary. The disadvantage of working at the motors in this manner is very obvious, for it is far easier to do this work if the body of the vehicle is removed, so that the workman can work from above with plenty of light instead of from below in semidarkness. In spite of this, however, the use of pits is still the most usual way of reaching the motors, and this is due to the difficulties which have been found in providing a truck which, while being staunch, durable, and easy-riding, can be taken apart at little cost and in a short time.

This is the general object of my invention, and to attain this object my invention resides in the provision of a truck having such a construction that upon the removal of a few fastenings the motors, motor-sustaining bars, wheels, axles, and axle-boxes form a substructure connected together, while the side bars, yokes, springs, sill-plates, and car-body form

a superstructure disconnected entirely from said substructure and adapted to be separated therefrom by a mere raising of the car-body, so that the motors may be inspected and repaired from above or an axle and its parts readily replaced. In my improved structure the substructure and superstructure are detachably connected in service—that is, the connection between the two structures is of such a nature that the mere removal of a few fastenings will without the necessity of altering the longitudinal or lateral positions of any of the main parts enable the structures to be vertically separated, as by lifting the superstructure.

My invention further resides in the more specific combination, construction, and arrangement of parts to be more fully set forth in the following description, whereby while maintaining the advantages of my basic invention I am enabled to utilize the motor-sustaining bars of my substructure to stiffen the truck as a whole, and whereby I obtain various other minor advantages.

The drawing accompanying and forming part of this specification is a side elevation of a truck embodying the various features of my invention.

A represents the axle-boxes, and B is one of the side bars, which is spring-supported upon said axle-boxes by means of semi-elliptic springs C, which at their centers rest on the top of the axle-boxes and at their ends are connected by links D or other suitable connections to the side bars B.

E represents one of the sill-plates to which the body of the vehicle is secured, and this sill-plate I have shown supported from the side bar B by semi-elliptic springs F and F'. The former are fastened at their centers to the two ends of the side bar, while links D' or other suitable fastenings secure the ends of the springs F to the sill-plates E. The spring F' is an inverted semi-elliptic spring, which I have shown connected at its center to the center of the sill-plate and at its ends to the side bar by links D'.

G represents yokes which are rigidly secured to side bars B and which straddle the axle-boxes A.

H represents one of the motor-sustaining

bars. These bars may support the motor in any of the specific ways well known to the art.

I have indicated at I a support for a cross-bar for what is ordinarily known as the "nose suspension." This, however, is obviously immaterial to any part of my invention.

The motor-suspension bar is of sufficient length so that its ends press outwardly against the outer legs G' of the yokes G, and this outward thrust is transmitted by means of trusses J to the ends of the side bars and aid in supporting the same. These trusses may be detachable members or they and the yokes may be cast integral with the side bars. 15 Bolts g connect the motor-sustaining bars to the inner legs G² of the yoke, so that, except for the thrust transmitted through trusses J by the downward pressure at the ends of the side bars, the motor-sustaining bars are supported entirely by the bolts g.

It will be seen that the motor-sustaining bars H, the axle-boxes A, the axles, the wheels, and the motors form the substructure before referred to, while the side bars B, yokes G, springs 25 F and F', and sill-plates E, with the car-body which they are intended to carry, are included in the superstructure. The only union between the super and sub structures other than that normally effected by gravity are the bolts 30 g. When these bolts are removed, there are no sockets, flanges, projecting parts, or other obstructions to prevent the upper structure from being bodily lifted from the lower structure, allowing the utmost facility of separation and ease in the repair of the parts of the substructure, in the parts of which all the elements which need frequent repair are included.

I prefer to connect the motor-sustaining 40 bars H to the axle-boxes just before separating the parts, and to do this I provide a very simple means for this purpose comprising a small yoke a, forming part of the axle-box A and having openings a', which register with 45 a hole provided in the bar H. Pins or bolts may be placed in these registering openings just prior to removing the bolts g, so that when the major part of the vehicle is lifted a unitary structure is left behind. The parts 50 are now separated in the best manner for inspection or repairs of the motors. If it is desired to renew a pair of wheels, it is now only necessary to block up one of the motors and disconnect it from the axle and its end of the 55 motor-sustaining bar from the axle-box to allow a pair of wheels to be rolled away from the remaining parts.

While I have shown and described an embodiment of my invention in the form of a 60 preferred construction, I do not at all limit myself to this specific construction nor to the use of all the features of my invention in a single truck, for the broad principles of my invention may be carried out in many different forms without departing outside the scope 65 thereof.

Having thus described my invention, what

I claim, and desire to protect by Letters Patent, is—

1. The combination, in a motor-truck, of a 70 pair of side bars supported by the axle-boxes, and a pair of motor-sustaining bars detachably connected to depending portions of said side bars, no portion of said side bars or their depending portions being beneath the under 75 side of said motor-sustaining bars when said connections are detached.

2. In a motor-truck, the combination of side bars spring-supported from the axle-boxes, 80 axle-box yokes carried by said side bars, motor-sustaining bars detachably connected to said yokes and serving as spreaders for the outer legs of the yokes, and trusses for supporting the outer ends of said side bars from the outer legs of said yokes. 85

3. In a truck, side bars spring-supported from the axle-boxes, yokes secured to said side bars, and trusses rigidly secured to the ends of the side bars and the outside arms of the yokes, in combination with motor-sustaining 90 side bars bearing against the outer legs of the yokes and detachably secured to the inner legs of the yokes.

4. An electric-motor truck composed of the combination of a superstructure supported on 95 the axle-boxes and including the side bars, springs and sill-plates for supporting the car-body, a substructure comprising the motors, motor-sustaining bars, axles and axle-boxes, said superstructure being vertically separable 100 from said lower member, and detachable fastenings between the superstructure and the motor-sustaining bars, normally upholding said motor-sustaining bars and preventing the aforesaid separation of the two members. 105

5. An electric-motor truck composed of the combination of a superstructure supported on the axle-boxes and including the side bars, axle-box yokes, sill-plates, and springs, a substructure including the motors, motor-sustaining 110 bars, axles, and axle-boxes, said superstructure being vertically separable from said substructure, and fastenings detachably connecting the motor-sustaining bars of the substructure and the axle-box yokes of the superstructure so as to normally uphold said 115 motor-sustaining bars and prevent the separation of the said superstructure and substructure.

6. An electric-motor truck, composed of the 120 combination of a superstructure supported on the axle-boxes and including the side bars, axle-box yokes, sill-plates and springs, a substructure including the motors, motor-sustaining 125 bars, axles, and axle-boxes, said superstructure being vertically separable from said substructure, fastenings detachably connecting the motor-sustaining bars of the substructure and the inner legs of the axle-box yokes of the superstructure and normally upholding 130 said motor-sustaining bars and preventing the aforesaid separation of the two structures, said motor-sustaining bars extending to, and bearing against the outer legs of

the said yokes, and trusses between the ends of the side bars and the outer yoke-legs.

7. In a truck, a pair of motor-sustaining bars supported by members depending from the side bars of the truck, and means for shifting the point of support for the motor-sustaining bars from the depending members to the axle-boxes of the truck.

8. In a truck, the combination of a pair of side bars, depending legs therefrom, motor-

sustaining bars secured to said legs, members depending from the axle-boxes, and registering holes in said members and in the motor-sustaining bars.

In testimony whereof I have affixed my signature in presence of two witnesses.

WILFRED E. BOUGHTON.
